CLAIM

The ornamental design for a display screen or portion thereof of a device with graphical user interface for a welding system, as shown and described.

DESCRIPTION

The FIGURE is a front view of a display screen or portion thereof of a device with graphical user interface for a welding system.

The outermost broken lines illustrate a display screen and form no part of the claimed design. The remaining broken lines illustrate portions of the graphical user interface and form no part of the claimed design.

1 Claim, 1 Drawing Sheet
